UNITED STATES PATENT OFFICE.

HOWARD S. KNEEDLER, OF PHILADELPHIA, PENNSYLVANIA.

DESIGN FOR TICKING OR SIMILAR WOVEN FABRIC.

SPECIFICATION forming part of Design No. 17,424, dated June 28, 1887.

Application filed May 5, 1887. Serial No. 237,279. Term of patent 7 years.

To all whom it may concern:

Be it known that I, HOWARD S. KNEEDLER, a citizen of the United States, and a resident of Philadelphia, Pennsylvania, have invented 5 a new and original Design for Ticking and other Woven Fabrics, of which the following is a specification.

My design for ticking and similar woven fabrics is illustrated in the accompanying drawings, in which—

Figure 1 is a view showing the general effect, and Fig. 2 is a view showing the detailed characters of the striped bars.

My design consists of alternating wide and 15 narrow bars A and B on a ground color, G, Fig. 1, the narrow bar B consisting of two bars, b b, each having two stripes, 1 2, with a third stripe, s, of a character which will give the effect of a shading to the bar b. The wide 20 stripe A consists of dark stripes 4 4 on opposite sides, and within them wider stripes 5 5, with narrow dark edges 6, shading off by means of stripes 7 into white stripes 8 and 9. Running through the stripe 9 is a narrow black 25 stripe, 10, while between the two stripes 8 and 9 lies a central bar, a, of two dark stripes. The central bar preferably merges into the stripe 9 by means of lighter stripes 11. The whole bar A has on one side a stripe, s, which 30 gives the effect of a shading to the bar. It will be observed that the shading-stripes s of the several bars are on the same side. In the

illustration the shading-stripe is shown on the right-hand side of each bar.

I claim—

1. The design for ticking and similar woven fabrics, said design consisting of alternating wide and narrow bars A and B on a ground, G, and each bar having on one side only a shading-stripe, s, which shading-stripes are on 40 the same sides of the several bars, all substantially as shown and set forth. 35

2. The design for ticking and other woven fabrics, said design consisting of wide and narrow bars A and B on a ground color, G, the 45 narrow bars being composed of narrow stripes 1 2, with shading-stripes s on one side of each two stripes, 1 2, while the wide bars have shading-stripes s on the side, and are composed of dark stripes 4 4 on opposite sides, and within 50 them wider stripes 5 5, with dark edges 6, shading off with stripes 7 into light stripes 8 and 9, a narrow black stripe running through the latter, and a two stripe bar, a, lying between 8 and 9, all substantially as shown and 55 set forth. 55

In testimony whereof I have signed my name to this specification in the presence of two subscribing witnesses.

HOWARD S. KNEEDLER.
